95,337

DESIGN FOR AN AUTOMOBILE OR SIMILAR ARTICLE

Robert S. Grimshaw, Detroit, Mich., assignor to General Motors Corporation, Detroit, Mich., a corporation of Delaware

Application January 6, 1934, Serial No. 50,339

Term of patent 14 years

To all whom it may concern:

Be it known that I, Robert S. Grimshaw, a citizen of the United States, residing at 20233 Stratford Road, Detroit, in the county of Wayne and State of Michigan, have invented a new, original, and ornamental Design for an Automobile or Similar Article, of which the following is a specification, reference being made to the accompanying drawing, forming part thereof.

Figure 1 is a side elevation of an automobile or similar article, showing my new design.

I claim:

The ornamental design for an automobile or similar article substantially as shown and described.

ROBERT S. GRIMSHAW.
